UNITED STATES PATENT OFFICE.

LESTER E. NORQUIST, OF DENVER, COLORADO.

ENTRANCE SWITCH.

Application filed September 5, 1924. Serial No. 736,055.

To all whom it may concern:

Be it known that I, LESTER E. NORQUIST, a citizen of the United States, residing at Denver, in the county of Denver and 5 State of Colorado, have invented certain new and useful Improvements in Entrance Switches; and I do declare the following to be a full, clear, and exact description of the invention, such as will enable 10 others skilled in the art to which it appertains to make and use the same, reference being had to the accompanying drawings, and to the characters of reference marked thereon, which form a part of this specification.

15 This invention relates to improvements in electric switches and has reference more particularly to a new and improved entrance switch.

It is the object of this invention to produce a switch of simple and substantial design that can be used in connection with cut-out cabinets of usual construction, and which shall have means adapted to interlock with the cover of the cabinet in such a manner 25 that the cover cannot be opened while the switch is in closed position.

The above and other objects that will become apparent as the description proceeds, are attained by means of a construction that 30 I will now proceed to describe in detail, reference for this purpose being had to the accompanying drawings, in which the preferred embodiment thereof is shown, and in which:

35 Fig. 1 is a vertical section through a portion of a cut-out cabinet and shows my switch in place therein;

Fig. 2 is a side elevation of the switch taken along line 2, Fig. 4;

40 Fig. 3 is a section taken on line 3—3, Fig. 4; and

Fig. 4 is a side elevation taken along line 4—4, Fig. 3.

45 Numeral 1 designates a metal cut-out box of ordinary construction having a trim 2 and a cover 3. The cover is hinged in the usual way. Both the cover and the trim are provided with notches 4 which form an elongated opening whose purpose will hereinafter appear. Secured to the bottom of the box 1, as by screws 5, I secure my combined switch and cut-out, which I will now describe.

50 This cut-out comprises a porcelain member having a base 6 from which projects a

perpendicular wall 7 to which the switch members and the fuse plug sockets are secured. On one side the wall 7 has two cup-shaped cavities, each of which contains a screw shell contact 8, which is electrically 60 connected to the terminal 9. The screw shell contacts are held in place by a screw 10 whose head 11 is insulated from the shell and forms a center contact. Screws 10 have threaded engagement with the switch contact clips 12 and serve to hold the latter, as well as the screw shells, in place. Secured to the wall 7 adjacent the base 6 are switch contact clips 13 which are held in place by 65 screws 14.

70 These clips have their sides perforated for the reception of a pivot pin 14^a about which the blades 15 oscillate. One side member of each clip has a portion 16 that projects toward the base and has its end bent outwardly into parallel relation with the latter. Binding screws 17 are threadedly connected to the outwardly bent ends and serve to clamp the ends of the service wires (not shown). The free ends of the switch blades 80 15 are connected by means of a bar 18 of insulating material. At a point intermediate the blades 15, I secure a bar 19, preferably of insulating material, to the outer end of which I secure a handle 20. It is evident 85 that the operator, by grasping the handle 20, can move the switch from open to closed position and vice versa. A barrier 21 is provided between the contact clips 13, and a similar barrier 22 separates the terminals 9. 90

The switch is secured to the bottom of the cut-out box in the manner shown in Fig. 1 and is so located with respect to the cover and the trim, that when the switch is in closed position, the bar 19 will extend 95 through the notch 4 in the edge of the cover. A plate 23 is attached to the bar 19 and is held against the outside of the box by means of a spring 24. The purpose of this plate is to close the oblong opening and prevent the 100 entry of dust and dirt, as well as to prevent fire from shooting out in case of a short circuit or the blowing of a fuse.

Before the cover 3 can be opened, it is necessary to move the bar 19 downwardly 105 until it enters that portion of the notch 4 that is located wholly in the trim. This opens the switch and releases the cover so that the latter can be opened. The interlock feature between the cover and the 110

switch insures that the cover cannot be opened until after the switch has been moved to open position.

From the above, it will be seen that by 5 means of my simple switch, I can obtain an interlock effect that has heretofore been obtained only by specially constructed cabinets and switches of complicated and expensive design. In addition to the interlocking feature, my switch also effects a considerable saving in the cost of the cabinets, for the reason that by having the switch in a plane vertical with respect to the bottom of the cabinet, when in closed position, it takes 10 up less room and makes it possible to use a smaller cabinet.

Having now described my invention, what I claim as new is:

20 A combined cut-out and entrance switch comprising, in combination, a body member of insulating material having a base, a wall projecting perpendicularly from one side

thereof, said wall having cylindrical recesses on one side for the reception of plug fuses, a knife switch secured to the other side of the wall, a screw shell and a center contact in each recess, a screw adapted to extend through the wall, a switch contact clip operatively related to each screw and held in place thereby, a pair of contact clips secured to the wall near the base, said last-named clips having terminals to which service wires may be connected, switch blades pivoted to the last-named clips and adapted to engage the first-named clips, an insulating bar connecting the free ends of the switch blades, and a handle secured to said bar, said handle being adapted to extend through a slot in a cabinet cover for the purpose of holding the latter against being opened while the switch is closed.

In testimony whereof I affix my signature.

LESTER E. NORQUIST.
